DESIGN FOR A BEAUTY MASK

Lucy Mehl, Long Island City, N. Y.

Application December 17, 1938, Serial No. 81,846

Term of patent 3½ years

To all whom it may concern:

Be it known that I, Lucy Mehl, a citizen of the United States and resident of Long Island City, in the county of Queens and State of New York, have invented a new, original, and ornamental Design for a Beauty Mask, of which the following is a specification, reference being had to the accompanying drawing, forming a part thereof, and of which Figure 1 is a view in front elevation of a beauty mask in flat open position, showing my new design, Fig. 2 is a view thereof in side elevation with the device as applied to the face of the wearer, and Fig. 3 is a vertical central sectional view thereof corresponding to Fig. 2.

I claim:

The ornamental design for a beauty mask, substantially as shown.

LUCY MEHL.
